Attorney

UNITED STATES PATENT OFFICE.

HAROLD L. RICHARDS, OF CRYSTAL FALLS, MICHIGAN.

GOLF TEE.

Application filed October 5, 1926. Serial No. 139,694.

This invention relates to golf tees and it is an object of the invention to provide a device of this kind to effect the desired supporting of a golf ball in a driving position and 5 wherein means is afforded for teeing the ball high or low as may be desired.

The invention consists in the details of construction and in the combination and arrangement of the several parts of my invention 10 provided golf tee whereby certain important advantages are attained and the device rendered simpler, less expensive and otherwise more convenient and advantageous for use, as will be hereinafter more fully set forth.

15 The novel features of my invention will hereinafter be definitely claimed.

In order that my invention may be the better understood, I will now proceed to describe the same with reference to the accompanying drawing, wherein:

Figure 1 is a view in elevation of a golf tee constructed in accordance with an embodiment of my invention;

20 Figure 2 is a view partly in elevation and partly in section of the tee as herein disclosed.

As herein disclosed, my improved tee comprises an elongated peg 1 of desired dimensions having one end portion pointed to 25 facilitate its insertion in the ground. The opposite end portion of the peg 1 is provided with a substantially concavo convex disc 2 of requisite dimensions affording a seat upon which the ball is adapted to be placed.

Threaded upon the peg 1, or shank as it 35 may be called, is a disc 3 of desired diameter and which is adapted, upon requisite turning movement relative to the peg or shank 1, to be adjusted lengthwise of the peg or shank to limit the extent of penetration of the peg 40 or shank and thus teeing the ball high or low as may be preferred by the player.

From the foregoing description it is thought to be obvious that a golf tee constructed in accordance with my invention is 45 particularly well adapted for use by reason of the convenience and facility with which it may be assembled and operated, and it will also be obvious that my invention is susceptible of same change and modification without departing from the principles and spirit thereof and for this reason I do not wish to be understood as limiting myself to the precise arrangement and formation of the several parts herein shown in carrying out my 50 invention in practice except as hereinafter claimed.

I claim:

A golf tee comprising an elongated peg 55 provided with a ball seat at one end portion and a disc threaded upon the peg for adjustment lengthwise thereof and operating to limit the extent of insertion of the peg within the ground.

In testimony whereof I hereunto affix my 60 signature.

HAROLD L. RICHARDS.
